UNITED STATES PATENT OFFICE

152,040

DESIGN FOR A DISPENSER FOR CANNED LIQUIDS

Francis J. Strodel, Liverpool, N. Y.

Application October 22, 1947, Serial No. 142,087

Term of patent 7 years

(Cl. D22—2)

To all whom it may concern:

Be it known that I, Francis J. Strodel, a citizen of the United States, residing at Liverpool, in the county of Onondago and State of New York, have invented a new, original, and ornamental Design for Dispenser for Canned Liquids, of which the following is a specification, reference being had to the accompanying drawing, forming part thereof.

Figure 1 is a rear perspective view of a dispenser for canned liquids, showing my new design, and

I claim:

The ornamental design for a dispenser for canned liquids, as shown.

FRANCIS J. STRODEL.
